B. B. MARTIN

TOY VEHICLE

Filed April 7, 1927.

UNITED STATES PATENT OFFICE.

BERT B. MARTIN, OF MARION, OHIO.

TOY VEHICLE.

Application filed April 7, 1927. Serial No. 181,780.

The present invention relates to an improved toy vehicle of the type including a platform on which the occupant is supposed to ride while in a standing position, the platform being suspended close to the surface, in order that it may be readily mounted or dismounted while moving.

More explicitly stated, the invention has reference to a structure of this kind which includes a low down platform supported at its rear end on a pair of comparatively small wheels and having at its front end a relatively large steerable wheel.

An important feature of the improved construction is a novel well braced standard having operating connection with the steering wheel and rotatable about a vertical axis and provided with hand grips. Incidentally the bracing means for this standard is of novel construction.

An equally important feature is a hand actuated lever which is carried by the standard and which has operating connection with the front steering wheel through the medium of novel means.

Other features of construction will become apparent from the following description and drawings.

In the accompanying drawings, forming a part of this application and in which like numerals are employed to designate like parts throughout the same:

Figure 1 is a side view of a complete toy vehicle, with a portion broken away and shown in section to expose the details more plainly.

Figure 2 is an enlarged fragmentary elevational and sectional view showing the construction of the forward portion of the toy, the section being taken substantially on the plane of the line 2-2 of Fig. 1.

Figure 3 is also a fragmentary sectional and elevational view, showing the standard mounting, the section being taken substantially on the plane of the line 3-3 of Fig. 2.

Fig. 4 is a top plan view, on a reduced scale, of the toy showing the general outline and the configuration.

Referring now to the drawings in detail, it will be seen that the reference character 1 designates the platform which is here shown as composed of metal. I call attention to the fact, however, that it may equally well be made of wood or any suitable ma-

terial. In the present instance, however, it is made of channel shaped cross section, the channel being open at its front and rear ends. The downturned flanges on the rear end are mounted upon an axle 2 on which a pair of small rubber tired wheels 3 are also mounted. The intermediate portion 4 of this platform is widened to provide a relatively wide supporting surface, for the occupant to stand on.

Attention is now invited to Figure 3, wherein it will be noticed that the reference character 5 designates an elongated block of wood which is swingably mounted between the side flanges of the platform. This extends before the forward end of the platform and is provided with side straps 6 of metal which is secured thereto in any appropriate manner. It will be noted that these straps extend a considerable distance beyond the forward end of the block and terminate in upwardly directed extensions 7, which have bearing openings formed therein for a crank axle 8, on which the front steering wheel 9 is mounted. It will be noticed that this wheel 9 is comparatively large in diameter with respect to the rear wheel 3. At the same time, the upwardly directed ends of the straps permits the platform to be supported in a level plane, and also permits the platform to be located in close spaced proximity to the surface over which the vehicle travels. The crank axle 8 is provided with crank arms 10, having crank pins 11. A pivot bolt 12 is connected with the block 5 and extends upwardly through an opening, 75 in the platform and is connected with a cross flange 13 on the lower portion of the standard 14. This standard comprises the metal plate 15 having spaced parallel side flanges 16. Also it is provided at the bottom 80 with a disc 17 rotatably resting on the top surface of the platform and fastened, as at 18, to the forward extending end of the block 5. With this arrangement it is obvious that the standard 14, the disc 17, the block 5, the 85 metal strap 6, and the front wheel 9 turn about a vertical pivot as a single unit, for permitting the vehicle to be steered. The side flanges of the platform opposite the block serve to form stops to limit the swinging movement.

Attention is now directed to a bracket 19 which is fastened to the intermediate por-

tion of the standard and which has its upper end formed into a retaining hook 20. A sleeve 21 surrounds this, and this sleeve constitutes a part of the brace 22. The 5 brace is made up of a pair of downwardly and rearwardly diverging arms 23, riveted or otherwise fastened to the platform in about the manner shown. Thus, while the standard is properly braced, the rotating 10 motion thereof is not interfered with, due to the swivel connection between the sleeve 21 and the bracket 19.

Attention is now called to the operating lever 24 pivotally mounted at a point between the middle and the one end on the 15 standard and extending through a slot 25 formed in the standard as shown in Figure 2. This lever is provided at its rear end with a suitable handle 26, and at its forward 20 end it is connected with a link 27 which extends downwardly and terminates in a fork 28. The arms of this fork straddle the wheel 9 and have their extremities curled around the crank pins 11, as at 29. This 25 provides a novel operating connection between the lever and the crank. Hence as the lever is rocked up and down on its pivot, the wheel 9 is rotated. The steering can be accomplished by swinging the lever from side 30 to side or by discretionary use of the hand grips 30, on the upper end of the standard.

From the foregoing description and drawings, it will be seen that I have produced a simple and inexpensive, well proportioned and easily operated toy vehicle, which is a novelty due to the method of propulsion and steering. It is sturdy and dependable in operation, being capable of movement either forwardly or rearwardly by 40 proper manipulation of the operating lever.

The parts have been carefully arranged to insure safe balancing and to withstand comparatively rough usage. The method of operation as well as the features of construction will be clear after reading the description in connection with the drawings. Therefore a more lengthy description is 45 thought unnecessary.

Changes in shape, size, proportions and 50 rearrangement of parts may be resorted to within the field of the adjoined claims.

I claim:

1. In a toy vehicle of the class described, a comparatively low platform, an axle at 55 the rear end thereof, comparatively small wheels mounted for rotation on the ends of the axle and on opposite sides of the platform, a single and comparatively large steering wheel located in advance of the forward end of the platform, and a steerable connection between the front wheel and said platform, said connection comprising a 60 block located on the under side of the platform, straps carried by and extending beyond said block, said straps being provided

with bearings, and said front wheel having a shaft rotatable in said bearings.

2. In a toy vehicle of the class described, a supporting platform of channel shaped cross section, a transverse axle supported in 70 bearings in the flanges at the rear end of the platform, a pair of comparatively small wheels mounted for rotation on the ends of the axle and on opposite sides of the platform, a comparatively large steering wheel 75 located in advance of the forward end of the platform, an elongated block disposed between the side flanges of the platform and the forward end of the latter, a pair of side straps fastened to said block and extending beyond the outer end thereof and terminating in upwardly directed extensions having 80 bearings, a shaft carried by said front wheel and rotatable in said bearings, a standard rising above said platform and having a disc at its bottom in rotatable contact with the top of the platform, a bolt connected with said block and with said standard, a connection between the disc and block, and hand grips on the upper end of the standard. 85

3. In a toy vehicle of the class described, a supporting platform of channel shaped cross section, a transverse axle supported in 90 bearings in the flanges at the rear end of the platform, a pair of comparatively small wheels mounted for rotation on the ends of the axle and on opposite sides of the platform, a comparatively large steering wheel located in advance of the forward end of the 95 platform, an elongated block disposed between the side flanges of the platform and the forward end of the latter, a pair of side straps fastened to said block and extending beyond the outer end thereof and terminating in upwardly directed extensions having 100 bearings, a shaft carried by said front wheel and rotatable in said bearings, a standard rising above said platform and having a disc at its bottom in rotatable contact with the top of the platform, a bolt connected with 105 said block and with said standard, a connection between the disc and block, hand grips on the upper end of the standard, a disc at its bottom in rotatable contact with the top of the platform, a bolt connected with said block and with said standard, a connection between the disc and block, hand 110 grips on the upper end of the standard, a bracket carried by the intermediate portion of the standard, a sleeve rotatable on said bracket, and depending brace arms connected with the sleeve and extending downwardly and rigidly connected with said platform. 115

4. In a structure of the class described, 120 a toy vehicle comprising a platform, rear supporting wheels, a front steering wheel, a steering connection between the front wheel and platform, a standard rising from the platform, a lever rockably mounted on the standard, a crank shaft carried by said 125 wheel and an operating link between the crank shaft and lever.

5. In a structure of the class described, 130 a supporting platform, rear wheels sup-

ported thereon, a front steering wheel, a standard mounted on a vertical axis on the platform and rising therefrom, an operating connection between the standard and front wheel, a lever rockably mounted on said standard, a crank shaft carried by said front wheel and including crank arms, a link con-

nected to the forward end of the lever and depending therefrom and provided with a fork, the arms of which straddle said wheel, ¹⁰ and a connection between the free ends of the fork arms and the said crank arms.

In testimony whereof I affix my signature.
BERT B. MARTIN.
